Attorney

UNITED STATES PATENT OFFICE

2,549,349

STORAGE RACK

Norman R. Wahlstrom, Los Angeles, Calif.

Application August 5, 1949, Serial No. 108,840

1 Claim. (Cl. 211—13)

1

This invention appertains to storage racks generally, and has for its object to provide one of a comparatively simple and inexpensive construction and arrangement of parts for the convenient and compact storage of a vacuum cleaner and its accessories for display purposes in stores, and more especially for use in small apartments and houses where storage space is at a premium.

In the drawings:

Figure 1 is a front elevation of a preferred embodiment of my invention;

Figure 2 is a rear elevation thereof;

Figure 3 is a vertical transverse section taken through the line 3—3 on Figure 2, looking in the direction of the arrows;

Figure 4 is an elevational view of one end of the same;

Figure 5 is a fragmentary horizontal section taken through the line 5—5 on Figure 2, looking in the direction of the arrows, and showing the form of clip for supporting the brush head of the vacuum cleaner;

Figure 6 is a fragmentary vertical section taken through the line 6—6 on Figure 2, looking in the direction of the arrows, and showing the form of clip for supporting the dusting brush attachment;

Figure 7 is a sectional view similar to that of Figure 6, but taken through the line 7—7 on Figure 2, looking in the direction of the arrows, and showing the supporting element for the upholstery cleaning accessory;

Figure 8 is a fragmentary sectional view similar to that of Figure 5, looking in the direction of the arrows, and showing the supporting clip for a vaporizer attachment for the vacuum cleaner; and,

Figure 9 is still another fragmentary sectional view similar to that of Figure 6, but taken through the line 9—9 on Figure 1, looking in the direction of the arrows, and showing one of the holders for the suction hose leading from the vacuum cleaner.

Referring to the drawings, wherein like characters of reference denote corresponding parts throughout the several views, the rack, in accordance with my invention, is comprised in a bottom wall 10 and end walls 12 and 14 which are substantially triangular in form. Extending between the upper narrower portions of the end walls 12 and 14 is a vertical partition 16 and laterally from the lower edge of the partition is a slightly upwardly and outwardly inclined shelf 20. The top edge of the partition 16 is formed with an apertured enlargement for use as a hand

2

grip, designated 18, in transporting the rack from one point of use to another.

In use, a cleaner body A is positioned on the bottom 10 of the rack and the suction hose H is led therefrom outwardly through a slot 22, opening through the front edge of the end wall 12, from whence it is trained upwardly along the outer side of the latter and inwardly of a cutout 24 formed in the top end of the same. From the cutout 24, the hose is laid along a substantial length of the top edge portion of the front side of the partition 16, where it is supported in a pair of spaced metal clips 26, as illustrated in Figures 1 and 9. From the clip 26 farthest 10 from the cutout 24, the hose H is trained downwardly in a return bend, so that a straight length of the same is supported in another of the clips 26, in parallel relation to and along a substantial length of the lower edge portion of the front side 15 of the partition 16. Here, the hose is trained in an upward direction in a second return bend for the support of its free end by a clip 28, such as is shown in Figures 1 and 8, the clip preferably 20 engaging with the nozzle N. The conductor cord C is led from the cleaner body A outwardly through a slot 30 opening through the front edge 25 of the end wall 14, where it is looped against the outer side of the wall and about a pair of vertically spaced hooks 32.

30 Mounted on the reverse, or rear, side of the partition 16 are the several accessories of the cleaner A, e. g., a floor brush head B by a metal clip 34 to the left center of the upper portion of the partition; a rug cleaner head R by a metal clip 36 to the right center of that portion of the partition; a dusting brush head B' by a stud 38 at a point below the inner end portion of the head B; an upholstery cleaning head U by a bolt or the like 40 at a point below the inner end of the head 35 R; a crevice or radiator cleaning head R' by a metal clip 42 horizontally below the two last named heads B' and U; a sprayer attachment S by a metal clip 44 secured in the end wall 14 above the shelf 20; and a vaporizer V by a metal 40 clip 46 secured in the end wall 12, also above the shelf 20. As shown in Figure 2, the sprayer S and the vaporizer V are thus supported above the ends of the shelf so as to provide a clearance between the same for the placing of wands or the like W on the shelf, where, due to the inclination 45 of the shelf, the wands are supported against accidental dislodgement therefrom.

50 From the foregoing, it will be obvious that I have provided a comparatively simple and inexpensive form of display or storage stand or

rack for a vacuum cleaner and its accessories, and an equally simple, inexpensive, and effective means, for supporting each of the parts and accessories in a position for direct observation and convenience in the removal and replacement of the same. Also, by the provision of the hand grip 18, at the center of the top edge of the partition 16, the stand or rack may be readily transported from one place of use, display, or storage, to another, without the possibility of dislodgement of the cleaner body, its parts and accessories, from their positions thereon.

Having thus fully described my invention in a preferred embodiment, it is to be understood that the words which I have used are words of description rather than of limitation and that changes within the purview of the appended claim may be made without departing from the true scope and spirit of the invention in its broader aspects.

What I claim is:

A rack for the display and storage of a vacuum cleaner and its accessories, comprising a bottom wall and vertical end walls, a partition disposed centrally of and vertically between the upper end portions of said end walls, a shelf extending to one side of the lower edge of said partition, means on one side of said partition to support the nozzle end of the suction hose leading from the cleaner body positioned on said bottom wall, means on one of said end walls to support the conductor cord leading from the cleaner body, means on the opposite side of said

partition to support the said accessories in a uniformly spaced relation one with respect to the other, the said end walls being substantially of triangular form, one of said end walls having a slot opening through its front edge below the plane of the lower edge of said partition and a cutout in its upper end for the training of the suction hose from the cleaner body outwardly of said slot and upwardly of the outer side of the wall and inwardly of said cutout for the support of its nozzle end in the means on the said one side of said partition, the other of said end walls also having a slot opening through its front edge below the plane of the lower edge of said partition for the passage of the conductor cord from the cleaner body outwardly through the same for the looping of the conductor cord about the said supporting means therefor, the latter means being comprised in a pair of hooks secured in vertically spaced relation on the outer side of the said other end wall.
